UNITED STATES PATENT OFFICE.

EDGAR L. LOGEE, OF PROVIDENCE, RHODE ISLAND.

DESIGN FOR A BADGE.

SPECIFICATION forming part of Design No. 34,468, dated May 7, 1901.

Application filed April 8, 1901. Serial No. 54,957. Term of patent 7 years.

To all whom it may concern:

Be it known that I, EDGAR L. LOGEE, a citizen of the United States, residing at Providence, in the county of Providence, in the 5 State of Rhode Island, have invented and produced a new and original Design for Badges, of which the following is a specification, reference being had to the accompanying drawings, forming part hereof.

Figure 1 is a front view of my design for a badge. Fig. 2 is a view of the same, partly in side elevation and partly in section, on line $\alpha\alpha$ of Fig. 1.

The essential features of my said design 15 consist of an annulus, within which, extending diametrically, is the representation of two

sections of a pipe united by a coupler and having a wipe-joint, emblematical of the plumber's trade. In the space beneath said diametrical figure is the representation of two 20 hands clasped together, a cuff or wristband being shown on each wrist.

What I claim is—

The design for a badge as herein shown and described.

In testimony whereof I have hereunto set my name in presence of two subscribing witnesses.

EDGAR L. LOGEE.

Witnesses:

JOSEPH R. BULLOCK, Jr.,
WARREN R. PERCE.
